DESIGN FOR A LADY'S ENSEMBLE DRESS

Renée Hall, New York, N. Y., assignor to Wolfsie
Knitting Mills, Inc., New York, N. Y., a corporation of New York

Application June 19, 1933. Serial No. 48,443

Term of patent 3½ years

To all whom it may concern:

Be it known that I, RENÉE HALL, a citizen of the United States, and a resident of New York, in the county and State of New York, have invented a new, original, and ornamental Design for a Lady's Ensemble Dress, of which the following is a specification, reference being had to the accompanying drawing forming a part thereof, in which:

Fig. 1 is a perspective of the ensemble dress viewed from the front;

Fig. 2 is a rear elevational view of the coat section of the ensemble dress disclosed in Fig. 1; and

Fig. 3 is a rear elevational view of the skirt section of the ensemble dress disclosed in Fig. 1.

I claim:

The ornamental design for a lady's ensemble dress, substantially as shown and described.

RENÉE HALL.
